UNITED STATES PATENT OFFICE.

ANTON BECKER, OF COLUMBUS, OHIO, ASSIGNOR TO THE RALSTON STEEL CAR COMPANY,
OF COLUMBUS, OHIO.

CAR.

No. 904,040.

Specification of Letters Patent.

Patented Nov. 17, 1908.

Application filed March 10, 1908. Serial No. 420,218.

To all whom it may concern:

Be it known that I, ANTON BECKER, of Columbus, in the county of Franklin and State of Ohio, have invented certain new 5 and useful Improvements in Cars; and I do hereby declare the following to be a full, clear, and exact description of the invention, such as will enable others skilled in the art to which it appertains to make and use the 10 same.

This invention relates to improvements in cars,—the object of the invention being to construct a steel underframe in such manner that it can be substituted for the 15 underframing of hopper-bottom gondola cars already constructed with other forms of underframe and thus providing, in the reconstruction of such cars, steel underframing.

With this object in view the invention 20 consists in certain novel features of construction and combinations and arrangements of parts as hereinafter set forth and pointed out in the claims.

In the accompanying drawings, Figure 1 25 is a plan view illustrating an application of my improvement. Fig. 2 is a longitudinal sectional view. Fig. 3 is an end view. Fig. 4 is a transverse section, and Fig. 5 is a de- 30 tail view.

1 represents a body of a gondola car provided with hopper-bottoms 2, the needle beams 3 which constitute the inner vertical walls of the respective hoppers being braced 35 and sustained by means of truss-rods 4, vertical rods or bolts 5 passing upwardly through said needle-beams and also by angle-irons 6 secured to a center girder 7. The center girder 7 (which sustains the load) has 40 secured to the respective channel members thereof, bolsters 8. Each of these bolsters comprises two members disposed at respective sides of the center girder and each member of the bolsters consists of plates 9 dis- 45 posed edgewise and provided at their upper and lower edges with angle-irons 10, the upper members of which constitute flanges projecting laterally from said plates. The inner end of each bolster member is secured to a 50 center girder member by means of an angle-iron 11 and to the outer end of each bolster member a bracket 12 is riveted and constitutes a depressed seat projecting beyond the end of the bolster member for the sup- 55 port of a side sill 13.

At each end of the center sill (the latter terminating inwardly of the ends of the car-body) draft sills 14 are provided. Each draft sill overlaps the end of a center girder member; is disposed in a lower horizontal 60 plane than that of the center girder, and is provided with an elongated slot 15 for the admission of the lower flange of the center girder member to which said draft sill is secured. This construction is most clearly shown 65 in the detail view, Fig. 5. In order to prevent any possibility of displacement between the center girder members and the draft sill members where they overlap, keeper plates 16 are provided and riveted to the center 70 girder members and to the draft sill members. The outer ends of the draft-sill members are slit and the upper portion bent outwardly and downwardly to form seats 17 for the end sills 18. Each end sill has a 75 width somewhat less than the length of the seat on the draft sill so as to leave room on the seats 17 for buffer blocks 19 and angle-irons 20 at the lower edges of said buffer blocks,—said angle irons being riveted to the 80 seats 17 and extending from one to the other. A channel iron 21 extends transversely across the seats 17 and from end to end of the end sill so as to form a facing for the latter. Each end sill is made of such depth that it 85 will project above the plane of the top of the draft sills and to provide an abutment for this upwardly projecting portion of the end sill, an angle-bar 22 is disposed across the tops of the draft sill members immediately 90 behind the end sill and is provided at its central portion with a strengthening rib 23. The angle-bar 22 is made of such length that its ends will project laterally beyond the respective draft sill members and the inter- 95 mediate portion of the abutment angle-bar is provided with flanges 24 which depend between the draft sill members and are securely riveted to the latter. Angle-bars 25 are also disposed behind the end sill at re- 100 spective sides of the draft sills, abut at their inner ends against the latter and are riveted thereto.

The needle-beams hereinbefore referred to may be made of wood and made to extend 105 upwardly beneath the floor line thereby forming walls for the hoppers which are sustained by the center girder.

In the construction of the bolster I prefer to make each member thereof of two parallel 110

plates each provided at its edges with angle-
irons as hereinbefore explained and the lower
angle-irons have secured thereto the end
portions of a tension plate 26 extending
5 under the center girder and upon each bolster
member is placed a cover plate 27 which is
riveted to the angle-irons at the upper edges
of the plates composing the bolster members.

Having fully described my invention what
10 I claim as new and desire to secure by Let-
ters-Patent, is,—

1. The combination with a center girder
and draft sills secured thereto and provided
15 with seats for an end sill, of an abutment
bar extending across the draft sills behind
the end sill seats and having flanges depend-
ing between the draft sills and riveted thereto.

2. The combination with a center girder
20 and draft sills fixed thereto, said draft sills
provided with seats for an end sill, of an
abutment bar disposed across the draft sills
behind the end sill seats, said abutment bar
provided with flanges depending between
25 the draft sills and secured thereto, and abut-
ments bars behind the end sill seats and se-
cured at their inner ends to the respective
draft sills.

3. The combination with a center girder
30 and draft sills fixed thereto, said draft sills
provided with depressed seats, and an end
sill supported on said seats, of a channel
iron constituting a facing for said end sill
and an angle iron abutment bar extending
35 across the draft sills behind the upper por-
tion of the end sill and secured to said draft
sills.

4. The combination with a center girder
40 provided at its lower edge with a lateral
flange, of a draft sill disposed in a lower
plane than that of the center girder and pro-
vided with a slot into which the lateral
flange of the center girder enters, and means
securing said center girder and draft sill
together.

45 5. The combination with a center girder
comprising channel-iron members, of draft
sills disposed in a lower plane than that of
the center girder, each of said draft sills pro-

vided at its rear end with a slot into which
the adjacent channel-iron member projects, 50
and means securing the draft sill members
to the center girder members.

6. The combination with a channel-iron
center girder, of a draft sill having its rear
end overlapping the forward end of the 55
center girder, and a keeper plate overlapping
the joint of said draft sill and center girder
and riveted to both.

7. In a hopper-bottom gondola car, the
combination with a center girder, of needle 60
beams below the floor line of the car and sus-
tained by said center girder and brace rods
passing vertically through said needle beams,
said needle beams constituting end walls for
the hoppers of the bottom. 65

8. The combination with a center girder,
of a bolster comprising members disposed at
respective sides of the center girder, each
of said members comprising a plate secured
70 at its inner end to a center girder member
and angle-irons secured to said plate at the
upper and lower edges thereof, a tension
plate secured at its respective ends to lower
angle-irons of the respective bolster mem-
bers, and brackets secured to the outer end 75
of each bolster member and constituting de-
pressed seats for end sills disposed beyond
the ends of said bolster members.

9. The combination with a center girder,
of a bolster comprising members disposed at 80
respective sides of the center girder, each
member of the bolster comprising two plates,
angle-irons secured at the upper and lower
edges of each plate, angle-irons securing
said plates to the center girder, a tension 85
plate extending under the center girder and
secured to the lower flanges of both bolster
members and cover plates secured to the up-
per flanges of the bolster members.

In testimony whereof, I have signed this 90
specification in the presence of two subscrib-
ing witnesses.

ANTON BECKER.
